[57] ABSTRACT

The machine comprises: a structural frame; a plate for supporting the piece of material with respect to said frame at least along the border to be turned-in; an in-setting device adapted to fold at right angles the border to be turned-in by means of a movement in a direction at right angles to said plate; a folding-back device adapted to turn back in a flat position against the support plate the border of the piece of material which has already been folded at right angles, by means of a movement parallel to said plate; and means for displacing the support plate in its own plane in the direction of displacement of the folding-back device in order to free the turned-in piece of material.

**MACHINE FOR TURNING-IN THE EDGE OF A
PIECE OF FLEXIBLE SHEET MATERIAL,
ESPECIALLY A TEXTILE FABRIC**

This invention relates to a machine for carrying out an operation which has been performed by hand up to the present time, namely which consists in turning-in the edge of a piece of flexible sheet material, especially a textile fabric.

The term "edge" as used in this description is intended to refer both to a portion of the border of the piece of material and to a portion or the complete periphery of an opening formed in a piece of material. This edge can also be a rectilinear or polygonal edge or alternatively a curvilinear edge.

The machine in accordance with the invention comprises: a structural frame; a plate for supporting the piece of material with respect to said frame at least along the border to be turned-in; an insetting device adapted to fold at right angles the border to be turned-in by means of a movement in a direction at right angles to said plate; a folding-back device adapted to turn back in a flat position against the support plate the border of the piece of material which has already been folded at right angles, by means of a movement parallel to said plate; and means for displacing the support plate in its own plane in the direction of displacement of the folding-back device in order to free the turned-in piece of material.

By means of this machine, the edges of pieces of material can be turned-in to wholly uniform dimensions, the work being performed on a quantity-production basis and consequently at an economical cost price.

In one advantageous embodiment, the machine is provided with means for urging the folding-back device against the turned-in border in order to press this latter against the piece of material, as well as a counter-plate provided with heating means and capable of being applied against the top of the piece, at least over the zone of the turned-in portion, in order to fasten the turned-in border by means of a thermo-adhesive substance which has previously been positioned against the back of the piece.

Fastening of the turned-in edge of the opening of the piece could also be carried out by means of a strengthening piece which would be glued in the cold state instead of being thermo-adhesive. Turning-in could also be carried out on the machine after gluing of the edge of the opening in the cold state or else in the hot state without adding any strengthening piece. It would also be possible to carry out the turning-in of the edges of the opening without placing any strengthening piece therein and without carrying out any gluing of the edges but simply by pressing these latter, preferably in the hot state, which would form a well-defined pleat.

The machine can be designed to receive pieces in which the opening has previously been cut; however, this preliminary operation involving cutting of the opening does not only result in a loss of time but makes it necessary, when placing the cut piece in position in the machine, to center said piece with accuracy in order to ensure that the turning-in is performed correctly on each side of the incision which has previously been made in the piece.

For this reason, it is an advantage to carry out the operation involved in cutting the opening of the piece of material in an automatic manner at the very begin-

ning of a turning-in cycle within the machine. To this end, provision is also made for a knife which is movable in a direction at right angles to the support plate in order to cut the part of flexible sheet material in order to prepare the opening for turning-in the edge of this latter; in the case in which the insetting device is constituted by a punch having a cross-section corresponding to that of the opening whose edge is to be turned-in and the folding-back device is constituted by a counter-punch, it is an advantage to mount the knife for sliding motion within the insetting punch.

By virtue of the presence of said knife, the piece of material which is introduced in the machine is first cut automatically in the location of its opening, the edges of said piece being then turned-in. By reason of the fact that the cutting knife is slidably mounted within the punch, centering of the cut with respect to the turning-in elements is carried out automatically, thereby ensuring perfect execution of the turning-in operation as well as achieving a saving of time.

The invention as described hereinafter will be explained more particularly in its application to the rectangular opening of the trousers pocket, this opening being consequently formed in a textile fabric. However, the invention could equally well be applied to the execution of many other operations such as the formation of a button-hole, for example. Moreover, the material to be treated need not necessarily be a textile fabric (whether woven, non-woven or of the mesh type) but could be a sheet of thermoplastic material, for example, or any other flexible sheet material, depending on the applications which may be contemplated.

A better understanding of the invention will be gained from the following description and from a study of the accompanying drawings which show by way of non-limitative example a few embodiments of a machine according to the invention which is more particularly intended to turn-in the edges of a rectangular opening of a trousers pocket.

In these drawings:

FIG. 1 is a profile view of a complete first embodiment of the machine, this view being taken in cross-section along line I—I of FIG. 2;

FIG. 2 is a top view of the machine, taken in cross-section along the chain-dotted line II—II of FIG. 1;

FIG. 3 is a front view of the complete machine, looking in the direction of the arrow III of FIG. 1;

FIG. 4 is a front view in which the assembly of turning-in jaws of the top portion of FIG. 3 is drawn to a larger scale;

FIG. 5 is a profile view corresponding to FIG. 4;

FIG. 6 is a sectional view taken along line VI—VI of FIG. 4;

FIG. 7 is a sectional view taken along the chain-dotted line VII—VII of FIG. 4;

FIG. 8 is a view which is similar to FIG. 4 and shows the components in another position;

FIG. 9 is a sectional view taken along line IX—IX of FIG. 8;

FIG. 10 is a sectional view taken along the chain-dotted line X—X of FIG. 12 and showing to a larger scale the heating-plate assembly of the top portion of FIG. 3;

FIG. 11 is a sectional view taken along line XI—XI of FIG. 10;

FIG. 12 is a sectional view taken along line XII—XII of FIG. 10;

FIG. 13 is a view to a larger scale, taken along line XIII—XIII of FIG. 11;

FIG. 14 is a partial sectional view to a larger scale and taken along line XIV—XIV of FIG. 11;

FIG. 15 is a sectional view taken along line XV—XV of FIG. 16, in which the sliding-plate assembly of the lower portion of FIG. 1 is illustrated to a larger scale, said plates being in a position of relative proximity;

FIG. 16 is a plan view which, in the upper half thereof, corresponds to FIG. 15 and, in the lower half thereof, shows the sliding plates in the relatively distant position;

FIG. 17 is a sectional view taken along the chain-dotted line XVII—XVII of FIG. 16;

FIG. 18 is a front view to a larger scale and showing the turning-in punch of the lower portion of FIG. 3;

FIG. 19 is a plan view corresponding to FIG. 18;

FIG. 20 is a sectional view taken along line XX—XX of FIG. 18;

FIGS. 21 to 24 illustrate the steps involved in forming the turning along the border of the opening provided in a piece of material in the machine which is illustrated in FIGS. 1 to 20;

FIG. 25 is a sectional view taken along line XXV—XXV of FIG. 26 and showing an alternative form of construction of part of the mechanism of the machine of FIGS. 1 to 20;

FIG. 26 is a plan view of the lower portion of FIG. 25;

FIG. 27 is a sectional view taken along line XXVII—XXVII of FIG. 26;

FIG. 28 is a sectional view taken along line XXVIII—XXVIII of FIG. 25;

FIGS. 29 to 33 illustrate the successive steps involved in forming the turning of the opening provided in a piece of material in a machine equipped with the punch and counter-punch of FIGS. 25 to 28;

FIG. 34 shows in perspective a piece of material in which an incision having the shape of a double Y has been made for the execution of a turning which is intended to form a rectangular opening in said piece;

FIG. 35 shows the piece of material of FIG. 34 after turning-in;

FIG. 36 shows in perspective another form of opening having a turned-in edge which can be made on a machine of the same type;

FIGS. 37 to 39 illustrate, by way of alternatives, portions which are turned-in along the outer border of a piece of material, these alternatives modes of operation being also permitted on a machine of the same type;

FIG. 40 is a vertical longitudinal sectional view of the insetting punch fitted with a cutting knife, this section being taken along line XL—XL of FIG. 42;

FIG. 41 is a vertical transverse sectional view taken along line XLI—XLI of FIG. 40;

FIG. 42 is a horizontal sectional view taken along line XLII—XLII of FIG. 40;

FIG. 43 is a horizontal bottom sectional view taken along line XLIII—XLIII of FIG. 40;

FIG. 44 is a transverse sectional view of the knife alone;

FIG. 45 is a longitudinal vertical sectional view of the complete folding-back punch, this view being taken along line XLV—XLV of FIG. 46;

FIG. 46 is a transverse vertical sectional view of the same assembly taken along line XLVI—XLVI of FIG. 45;

FIGS. 47 to 52 illustrate the successive steps involved in cutting and turning-in the opening of a piece of material in a machine equipped with the punch and counter-punch of FIGS. 40 to 46.

The machine for turning-in the edges of a rectangular opening formed in a piece of material which has previously been cut to the shape of a double Y as illustrated in FIG. 34, comprises a structural frame which is generally designated by the reference 1 (as shown in FIGS. 1 to 3) and which supports all the components of the machine. This frame may rest if necessary on legs or standards (not shown in the drawings).

The structural frame 1 is fitted with three small columns 2, 3, 4 for supporting a frame 6 in which the piece of material to be turned-in is placed. The machine comprises elements which are located above said frame and elements located beneath this latter.

The elements located above the frame 6 essentially comprise an insetting and folding-back assembly 11, a heating counter-plate 12 which is intended especially to effect the melting of a thermo-adhesive reinforcement along the periphery of the opening whilst the elements which are located beneath the frame 6 are essentially constituted by a wedge 13 for actuating the folding-back assembly 11, and a set of sliding support-plates 14 which are intended to support the material at least along the edge portion of the opening to be turned-in during the operation of the insetting and folding-back assembly and during the operation of the heating plate.

The frame 6 for supporting the piece to be turned-in is formed by an upper sheet-metal plate 21 and a lower sheet-metal plate 22, each plate being of generally rectangular shape and pivotally mounted along one edge by means of a hinge-pin 23. These two plates are provided with a rectangular opening 24 (shown in FIG. 2) having sufficient dimensions to permit the heating counter-plate 12 to pass therethrough, said counter-plate being intended to cooperate with the support plates 14. The front edges of the two plates 21, 22 of the frame 6, that is to say the edges of these latter which are opposite to the hinge 23, are lifted as shown at 25, 26 in FIG. 1 both for convenience of handling operations and also in order to form therebetween a space within which it is possible to roll the remainder of the piece of material if so required.

The lower ends of the small columns 2, 3, 4 are fixed on a lower sheet-metal member 27 of the structural frame 1 of the machine; in the example illustrated, said columns are tubular and the frame 6 rests on the upper ends of these latter, is accurately positioned thereon and maintained by means of a locking system comprising a horizontal arm 31 whose two extremities are provided respectively with two conical studs 32, 33 which are intended to engage at the same time in corresponding holes formed in the two plates 21, 22 of the frame 6 and in the orifices of the upper ends of the three columns. The arm 31 is supported by the lower end of the piston rod 36 of a small vertical compressed-air jack 37. The cylinder 38 of said jack is fixed on a right-angle bracket 39 which is in turn secured to a horizontal stirrup-member 41, the two arms of which are welded at the extremities thereof to a vertical wall 42 of the frame of the machine.

The insetting and folding-back assembly 11 is illustrated in detail in FIGS. 4 to 7. This assembly essentially comprises a plate 46 of rectangular shape corre-

sponding substantially to the dimensions of the opening to be turned-in and rigidly fixed to a vertical cylindrical rod 47 which is capable of sliding within an upper guide 48 (as also shown in FIGS. 1 and 3), said guide being rigidly fixed to the vertical wall 42 of the frame of the machine. The plate 46 is positioned angularly with respect to the axis of the rod 47 by means of two guide rods 51, 52 which are also rigidly fixed to said plate and are capable sliding within corresponding vertical bores of the guide 48.

There are fixed in the vicinity of the two ends of the plate 46 two small vertical plates 53, 54 for supporting the two ends of a hinge-pin 55 which carries two large pallets 56, 57 each having an L-shaped cross-section. The long arm of the L is substantially vertical and pivotally mounted on the pin 55 whilst the short arm is substantially horizontal and curved outwards. These two large pallets are urged to pivot in the direction which brings them towards each other in back-to-back relation (as shown in FIG. 6) under the action of springs such as the spring 58, one extremity of which is attached to the end of a corresponding upward extension 59 or 61 of the corresponding pallet and the other extremity of which is attached to a lug 62 which is rigidly fixed to the plate 46. Stops 63, 64 serve to limit the amplitude of pivotal motion of said extension under the action of the springs.

In like manner, this insetting and folding-back assembly also carries two small end-pallets 67, 68 also of L-shaped cross-section and hinged on pins 71, 72 carried by small plates such as the two small plates 73, 74, for example, which are fixed beneath the corresponding end of the plate 46. These two small pallets are also provided with extensions 75, 76 (shown in FIG. 4) which are subjected to the action of restoring springs 77, 78 in the direction of withdrawal of the pallets; stops 81, 82 serve to limit these movements. The two springs 77, 78 are attached to lugs 83, 84 which are rigidly fixed respectively to the two ends of the plate 46.

There can be seen in FIGS. 8 and 9 the pallets 56, 57 and 67, 68 which have been separated from each other under the action of means which will be described hereinafter.

The insetting and folding-back assembly 11 is urged upwardly elastically by a helical compression spring 86, one extremity of which bears on the upper face of the guide 48 and the lower extremity of which is applied against a washer 87 which is retained in an axially adjustable position on the rod 47 by means of a nut 88 and a lock-nut 89 mounted on the threaded upper end of the rod 47. There is mounted within the upper end of said rod 47 a screw 91 which is locked in position by means of a lock-nut 92, there being fixed on the head of said screw a cap 93 which is intended to be subjected to the downwardly-directed force applied in opposition to the spring 86 to the insetting and folding-back assembly 11 under the action of a mechanism comprising a disc-cam 96 (shown in FIGS. 1 and 2), a cam-follower roller 17 which is in contact with said cam and carried by an arm 98, another arm 99 rigidly fixed to the arm 98, and a roller 101 carried by the arm 99 and in contact with the cap 93 mounted on the upper extremity of the rod 47 which carries the insetting and folding-back assembly 11.

The disc-cam 96 is fixed on a shaft 103 which is pivotally mounted in two bearings 104, 105 (as also shown

in FIGS. 2 and 3) which are carried by two end-plates 106, 107 of the frame of the machine. The arm 98 has a hub 109 which is capable of rotating on a sleeve 111 and this latter is in turn mounted to rotate freely on a shaft 112, the two ends of which are also supported in the two end-plates 106, 107 of the frame. The arm 99 is also fixed on the hub 109.

The shaft 103 which carries the cam 96 is driven in slow rotational motion by means of any suitable driving system (not shown in the drawings).

The heating counter-plate assembly 12 is shown in detail in FIGS. 10 to 14. This assembly comprises an electric resistance wire 121 fitted within a peripheral groove formed between two plates 122, 123 which are fixed together on the lower ends of four small columns 124, the upper ends of which are secured by means of insulating bushings 126 to an upper plate 127, said plate being in turn secured to the lower ends of two vertical rods 128 which also slide within the guide 48.

The heating counter-plate assembly 12 is urged upwards by means of helical springs 131 in the same manner as the insetting and folding-back assembly. The upper plate 127 has a central hole 133 through which the supporting rod 47 of the insetting and folding-back assembly is permitted to pass and two further holes 134 for the insertion of the rods 51, 52 for angular positioning of said assembly.

The heating plate is provided with heat-storage means constituted by two parallelepipedal blocks 136, 137 which are attached respectively to the plates 122, 123 by means of screws 138, 139 respectively. The block 136 is provided with an opening 141 for the lead-in and lead-out of the resistance wire 121 whilst the block 137 has a longitudinal recess 143, there being housed in said recess a probe 144 which is incorporated in a circuit (not shown) for regulating the temperature of the heating plate.

The heating-plate assembly 12 can be moved downwards in opposition to the springs 131 by means of another disc-cam 145 which is also fixed on the shaft 103 (as shown in FIGS. 1 and 2) and produces action on an arm 146, said arm being rigidly fixed to the sleeve 111 which carries two other arms 147, 148 terminating in rollers 149, 150 (shown in FIG. 3) which bear on the top faces of caps 151 mounted on the upper extremities of the two rods 128 which support the heating-plate assembly 12.

The wedge 13 (shown in FIG. 1) for actuating the pallets of the insetting and folding-back assembly is illustrated in detail in FIGS. 18 to 20. Said wedge is formed of a bar 161 of generally parallelepipedal shape, the two ends of which are tapered to a point and the upper face of which is provided with a longitudinal rib 162 in the form of a dihedral angle, the edge of which is located at the top; the end faces of said rib are also inclined substantially at the same angle, as shown at 163, 164. The top face of the rod 161 is also provided with a peripheral rib 166, the top face of which is flat and the height of which is smaller than that of the longitudinal central rib 162.

The bar 161 is fixed on the upper extremity of a vertical rod 168 which is capable of sliding within a lower guide 169 (see also FIG. 1) which is also fixed on the front face of the vertical wall 42 of the frame of the machine. Angular positioning of the bar 161 about the axis of the rod 168 is ensured by means of two rods 171 which are parallel to the central rod 168, said rods

being disposed on each side of said central rod and capable of sliding within corresponding holes of the lower guide 169.

The wedge 13 is urged downwards elastically by a helical spring 172, one extremity of which is applied against the underface of the guide 169 and the other extremity of which is applied against a washer 173 which is maintained on the threaded lower end of the rod 168 by means of a nut 174 and a lock-nut 175. There is mounted within the lower end of the rod 168 a screw 176 fitted with a cap 177 and a locking counter-nut 178.

The wedge 13 can be caused to move upwards in opposition to the spring 172 by means of a system comprising a disc-cam 182 (shown in FIGS. 1 and 2) which is also fixed on the shaft 103 and cooperates with a roller 183 mounted on an arm 184 which pivots on a lower shaft 185 which is also supported at both ends by the end-plates 106, 107 (shown in FIG. 2) of the frame of the machine, and another arm 186 (shown in FIG. 1) which is coupled to the arm 184 and the extremity of which carries a roller 187, said roller being in contact with the cap 177 and this latter being rigidly fixed to the rod 168 which serves to support the wedge 13.

The assembly of support plates 14 is shown in detail in FIGS. 15 to 17. Said assembly comprises a bottom plate 192 fixed on the upper ends of two rods 193 which also slide vertically within the lower stationary guide 169. These two rods are also subjected elastically and downwardly to the action of two helical compression springs 194. The lower ends of the two rods 193 carry two screws 196 fitted with caps 197.

The bottom plate 192 is provided with a central open portion 201 through which is passed the rod 168 (shown in FIG. 18) which carries the wedge 13 and with two other open portions 202 for passing through these latter the two rods 171 which serve to guide said wedge.

Two small vertical plates 205, 206 are secured to the two opposite ends of the bottom plate 192 by means of screws 204. The ends of two stirrup-members 208, 209 are secured against the ends of the two small plates aforesaid by means of screws 207 and support respectively two small compressed-air jacks 212, 213.

There is fixed on top of the small plates 205, 206 a plate 216 having an open structure on which are slidably mounted two support plates 217, 218 each having one-half of the central opening 219 of rectangular shape which is identical with that of the textile fabric opening to be turned-in. These two sliding plates 217, 218 are capable of taking-up either the position of relative proximity which is illustrated in FIG. 15 and in the upper half of FIG. 16, or the position of relative withdrawal in which said plates are separated from each other as shown in the lower half of FIG. 16. This movement is produced by the two jacks 212, 213 which are coupled respectively to said plates by means of the piston rods 221, 222 of said jacks, of cross-pins 223, 224, and of bearing-brackets 225, 226 rigidly fixed to two blocks 227, 228 which are in turn secured to the two sliding plates by means of screws 231, 232.

The blocks 227, 228 have a T-shaped cross-section and retain the two sliding plates in the upward direction, the top portion of each block being in the form of a lug and capable of sliding within corresponding openings 233, 234 of the plate 216. Said plate 216 is further provided with a central rectangular opening 236

through which the wedge 13 is intended to pass (as shown in FIGS. 18 and 20).

Those parts of the two sliding plates 217, 218 which are located in the vicinity of the opening 219 have a hollowed-out portion 238 of small depth which is equal to the thickness of a thermo-adhesive reinforcement for fixing the turning, as will be explained hereinafter.

The assembly of sliding plates 14 can be moved upwards in opposition to the spring 194 by means of a disc-cam 241 (shown in FIGS. 1 and 2) which is also fixed in the shaft 103 and against which is applied a follower-roller 242 carried by an arm 243 rigidly fixed to another arm 244 which, in an arrangement similar to that described earlier in connection with the operation of the heating-plate assembly 12, comprises said arm 244 and another arm 245 (see also FIG. 3), both arms being rigidly fixed to a common sleeve which also carries the arm 243 and is mounted to rotate freely on the lower shaft 185. The two arms 244, 245 carry rollers 246, 247 which are intended to lift the capes 197 (shown in FIG. 17) which are fixed on the lower extremities of the rods 193 for controlling the slidingplate assembly 14.

The operation of the machine is as follows:

It will be assumed that the operation to be performed consists in turning-in four edges 261, 262, 263 and 264 (shown in FIG. 35) of a rectangular opening 265 formed in a piece of material 266 in which an incision 267 having the shape of a double Y (as shown in FIG. 34) had previously been made by any suitable conventional method, the piece of material being preferably already placed in position within the frame 6 which has been removed from the machine, in order to avoid any subsequent problem of centering of the cut piece of material with respect to the frame. It will also be assumed that this turning-in operation is performed around a thermo-adhesive reinforcement piece 268 (shown in FIG. 35) provided with a rectangular opening having the same dimensions as the opening 265, the edges of which are to be turned-in.

The thermo-adhesive reinforcement piece 268 is placed within the hollowed-out portions 238 of the sliding support plates 217, 218 (shown in FIGS. 15 and 16) which are located in the position of relative proximity. The frame 6 (FIGS. 1 and 2) is opened, the piece to be turned-in is placed therein, the frame is closed again and laid on the small columns 2, 3, 4. By way of alternative, the thermo-adhesive reinforcement piece could have been placed beforehand, either by hand or automatically, directly against the piece of material before placing this latter within the frame 6.

The jack 37 is supplied in such manner as to ensure that the frame 6 is accurately placed and maintained in position in the machine by means of the conical locking studs 32, 33. The insetting and folding-back assembly 11 as well as the heating plate 12 take up their top positions whilst the wedge 13 and the sliding support plates 14 which are located in relative proximity, take up their bottom positions. The heating plate 12 is at its normal operating temperature.

The shaft 103 (shown in FIGS. 1 and 2) which carries the cams is driven, for example, from an electric motor which is started-up automatically when the jack 37 which locks the frame 6 has reached the end of its frame-locking travel.

The insetting and folding-back assembly 11 thus moves downwards as well as the heating plate 12 while the sliding support plates 14 and the wedge 13 move upwards. The kinematics of the assembly are so designed and arranged that the initial stage of the cycle consists in causing the pallets such as 56, 57 of the insetting assembly to move downwards onto the borders of the piece of material 266 (shown in FIG. 21) in such manner as to fold said borders downwards at right angles, progressively as said pallets move down from the position shown in FIG. 21 to the position shown in FIG. 22. The four sides of the opening are therefore already folded-back at right angles by the four pallets of the insetting assembly 11. In the meantime, the wedge 13 has moved towards the pallets 56, 57. During the following stage, the active rib 162 of said wedge engages between the pallets 56, 57, thereby outwardly displacing these latter and causing them to change-over from the position of FIG. 22 to the position of FIG. 23; during this stage, the pallets perform the function of folding-back device in order that the borders of the piece 266 which have previously been folded at right angles by the pallets in their role of insetting device should be turned-back and applied in a flat position against the support plates 217, 218. During this time, the heating counter-plate 12 has moved downwards against the piece 266. The thickness of the small flanges of the pallets comes into position within the space formed between the central rib 162 of the wedge 13 and its peripheral rib 166. The sliding plates 217, 218 move away from each other under the action of their pneumatic control jacks 212, 213 which are accordingly supplied automatically, for example. Under the action of its suitably profiled control cam 182, the wedge 13 again moves upwards over a short distance corresponding to the value of the thickness of the support plates 217, 218 and effectively flattens the folded-back edges of the material against the reinforcement piece 268 (shown in FIG. 24), the insetting and folding-back assembly 11 having in turn moved upwards by the same amount under the action of its control cam 96. The heat supplied by the counter-plate 12 ensures melting of the thermo-adhesive reinforcement 268 whilst the turned-in portion of the piece is tightly applied against said heating counter-plate. This results in final fixing of the turned-in edges of the materials (as shown in FIG. 35).

The cycle continues with the downward motion of the wedge 13, the closing motion of the pallets of insetting and folding-back assembly under the action of their restoring springs, as well as the downward motion of the sliding support plates 217, 218, whilst the heating counter-plate and the insetting and folding-back assembly move up again to their starting position for the following cycle. The frame 6 is released by actuating the jack 37; it then only remains to remove said frame from the machine and to open this latter in order to extract the turned-in piece therefrom. The sliding support plates 217, 218 are again brought together in order that the machine should be ready for the following cycle.

In the examples contemplated in the foregoing, it has been assumed that the operation to be performed consisted in turning-in the edges of a rectangular opening. However, this shape is clearly not limitative and it would be possible to make use of a machine based on the same principle in order to turn-in the edges of an opening having any shape such as a polygonal or curvilinear shape as shown by way of example in FIG. 36 and

designated by the reference 271. Instead of the intended application which consists in turning-in the edges of an opening, it would also be possible to carry out the turning-in of an outer edge of a piece of material, whether this edge is rectilinear such as the edge 272 shown in FIG. 38 or curvilinear such as the edge 273 shown in FIG. 37, and whether it proves necessary to fold-back only a single portion 272 (FIG. 38) or a number of portions 272, 273, 274 (FIG. 39) of said edge.

There is illustrated in FIGS. 25 to 28 an alternative form of machine which differs from the machine described in the foregoing in the fact that the insetting device is constituted by a simple rigid punch 301 whilst the folding-back device is constituted by an assembly of components forming a counter-punch 302 which is separate from the insetting device, the upper heating-plate assembly and the assembly of lower sliding plates being retained as well as their actuating members.

The punch 301 is constituted by a solid part having a rectangular cross-section equal to that of the opening to be turned in; said punch is attached to the vertical sliding rod 47 which, in the machine hereinabove described, supported the insetting and folding-back assembly.

The counter-punch 302 is formed of four members 304, 305, 306, 307 of which the upper portions 311, 311A, 313, 313A can be applied against each other as shown, in such manner as to constitute a generally rectangular cross-sectional assembly having exactly the same dimensions as the cross-section of the punch 301.

The two main members 304 and 305 are two identical profiled components. The member 304, for example, has a C-shaped cross-section in which the upper arm is provided with an upwardly elbowed extension 311 forming one of the four active elements of the counter-punch. The member 305 has a corresponding element 311A and the thickness of the assembly formed by these two juxtaposed elements is equal to the width of the opening to be turned-in.

The active portion of the member 306 is constituted by a small vertical prism 313 having a cross-section in the shape of an isoscele triangle which is accurately fitted against two bevelled faces 308, 309 formed along the corresponding vertical inner edges of the two members 304 and 305. The corresponding active portion 313A of the member 307 is similarly fitted in position against two bevelled faces of the opposite inner vertical edges of the two members 304 and 305 in such manner that the complete assembly of active portions 311, 311A and 313, 313A should have a rectangular cross-section which is identical with that of the opening to be turned-in.

The four members which constitute the counter-punch are mounted in such manner as to be capable of withdrawing from each other in order to carry out the turning-in of the edges of the opening formed in the piece of material. To this end, the member 304, for example, is fixed on the head end of a shouldered screw 315, the smooth portion of which is capable of sliding horizontally within a bore 316 of a support 317 which is rigidly fixed to a rectangular plate 318. The member 305 is similarly supported by a sliding screw 315A mounted in a support 317A which is fixed on the other end of the plate 318. Two springs 321, 321A, which are fitted over the screws 315, 315A and interposed be-

tween the internal faces of the two supports 317, 317A and the external faces of the two members 304, 305 of the counter-punch, urge these two members towards each other.

The heads of two screws 322, 323 mounted respectively in two horizontal lugs 324, 325 which are rigidly fixed to the lower portion of the member 304 are in contact with the top face of the plate 318 and serve to prevent the member 304 from pivoting about the axis of the screw 315 which supports this latter, in order that said member should remain horizontal. Two identical screws 322A, 323A serve to maintain the opposite member 305 of the counter-punch in a horizontal position.

The active triangular member 306 of the counter-punch is fixed on a right-angle bracket 326, this latter being in turn secured to the end of a shouldered screw 317 which is capable of sliding within a horizontal bore 328 of a support 329 fixed on the top of the plate 318. Similarly, the other triangular active portion 313A of the counter-punch is carried by a right-angle bracket 326A and this latter is secured to a screw 327A which slides within a support 329A. The two right-angle brackets and consequently the two active triangular portions 313, 313A of the counter-punch are urged towards each other under the action of two springs 331, 331A. Horizontally of the two right-angle brackets 326, 326A is ensured by two screws 331 and two screws 331A respectively, the heads of which bear on the top face of the plate 318.

The two members 304, 305 on the one hand, and the two members 306, 307 on the other hand, can be moved away from each other in opposition to their restoring springs by means of two cams 334, 335 respectively having substantially the shape of flattened ellipses, said cams being keyed at an angular interval of 90° with respect to each other on a vertical shaft 336 pivotally mounted in a bushing 337 which is inset at the center of the plate 318. The end faces of the edges of the lower arms of the C-shaped sections of the two members 304, 305 are applied against two diametrically opposite points of the cam 334 whilst the end faces of the extremities of two horizontal fingers 338, 338A which are integral with the two right-angle brackets 326, 326A are applied against two diametrically opposite points of the cam 335. In the position shown in the drawings, the aforesaid end faces of the four members are applied against the flattened portions of the two cams and the corresponding active portions of the counter-punch are juxtaposed. In order to move them away from each other for the purpose of turning-in the edges of the opening formed in the piece of material, it is only necessary to produce a pivotal movement of the shaft 336 through an angle of 90° by means of any suitable drive system (not shown) in order to ensure that the active end faces aforesaid should be thrust back by the two cams until they come into contact with the two diametrically opposite points located on the major axes of these two cams.

The plate 318 is adapted to carry two tubular guides 341, 342 which bear on the underface of said plate and are capable of sliding along two rods 343, 344 respectively, the lower ends of said rods being in turn fixed on a horizontal plate 345 which is rigidly fixed to the frame of the machine. The counter-punch assembly is urged upwards elastically by means of a spring 347, the lower end of which is applied against the top face of the

plate 345 and the upper end of which is applied against the underface of a cross-piece 348 which is rigidly fixed to the lower ends of the two tubular guides 341, 342. The spring 347 is intended to apply the top face of the counter-pinch elastically against the bottom face of the punch whereas it is possible on the contrary to move the counter-punch downwards in opposition to said spring by means of a cam 351 also having substantially the shape of an ellipse and keyed on a horizontal drive shaft 352 supported by two bearings (not shown) which are rigidly fixed to the stationary plate 345. Said cam can be driven by any suitable and conventional means such as a manual control lever, for example, which is indicated diagrammatically by the reference 353. It would also be possible to control the downward motion of the counter-punch 302 by means of a disc-cam and lever mechanism of the type employed in the machine hereinabove described for controlling the wedge which serves to open the folding-back assembly.

The operation of this alternative embodiment is as follows:

When the piece of material 266 having an opening to be provided with a turned-in hem has been placed within the frame 6 which has been suitably positioned on the frame of the machine as already explained in connection with the machine of FIG. 1, and when the thermo-adhesive reinforcement piece 268 has also been placed in position, the initial stage of the cycle consists in the downward displacement of the punch 301 which moves from the position of FIG. 29 to the position of FIG. 30 while folding at right angles the four edges of the slit 267 having the shape of a double Y which has previously been formed in the fabric. At the end of travel, the punch 301 is applied against the top of the counter-punch 302 and thrusts this latter downwards to a slight extent in opposition to the spring 347 (as shown in FIG. 27) in order to ensure that the counter-punch is effectively applied against the punch.

The following stage which is illustrated in FIG. 31 is a simultaneous partial upward return of the punch and counter-punch assembly so as to bring the top face of the counter-punch 302 exactly to the level of the sliding support plates 217, 218.

In the following stage, the four members of the counter-punch move away from each other (as shown in FIG. 32) and the borders of the opening in the material which have already been folded at right angles are folded-back in a flat position. The sliding plates are then moved away from each other (as shown in FIG. 33) and the assembly consisting of punch 301 and counter-punch 302 moves upwards over a distance corresponding to the thickness of said sliding support plates in order that the turned-in portions of the material should be firmly applied against the heating counter-plate 12 which has come into position at the same time in order to be applied against the top face of the material. As a result of the combined actions of pressure and heating of the plate, the edges of the material are fixed finally in their turned-in configuration.

The alternative embodiment shown in FIGS. 40 to 46 makes it possible to carry out the operation involved in cutting the opening of the piece in an automatic manner at the very beginning of a turning-in cycle in the machine.

Only the structural design of the insetting punch will now be described in detail since the whole of the remainder of the machine including the erection and the

devices for controlling the punch and counter-punch, as well as the means for positioning and supporting the piece of material having an opening to be turned-in, are the same as in the machine described in detail in the foregoing, more particularly with reference to FIGS. 25 to 28.

The insetting punch assembly 401 is associated with a knife assembly 402 and with the heating counter-plate assembly 12, the structural design of which is described in detail in the foregoing.

The insetting punch assembly 401 is essentially constituted by two parallel longitudinal plates 405, 406 of rectangular cross-section which constitute the two main members and by two prisms 407, 408 in the form of isosceles triangles constituting two auxiliary members which are adapted to engage between vertical bevelled portions of the extremities of the internal faces of the two main members, as shown in particular in FIG. 43.

The two main members 405, 406 are provided with angled upper extensions 411, 412 by means of which said members are supported by screws 413, 414 in the bottom portions of two vertical spacer-arms 415, 416 which are in turn fixed against the underface of a horizontal plate 418. This plate is in turn fixed on the lower ends of two vertical rods 421, 422 and these latter are slidably fitted within corresponding vertical guides (not shown) which are rigidly fixed to the frame of the machine. Four vertical screws 425 which are fixed in the plate 418 are applied by means of their heads against the top face of the extensions 411, 412 of the two main members of the punch so as to absorb the stress sustained by said punch and to relieve the lateral screws 413, 414.

In a similar manner, the two auxiliary triangular members 407, 408 of the punch are provided with extension 431, 432 carried by two horizontal screws 433, 434 also mounted in the lower ends of vertical spacer-arms, the upper ends of which are fixed beneath the same plate 418.

The knife assembly 402 is constituted by the knife 411 proper and by a mounting-strip 442 fixed on the lower end of a vertical rod 443 which slides along the axis of the assembly within guides (not shown) which are also rigidly fixed to the frame of the machine. The rod 443 passes freely through a central hole 445 of the plate 418. The knife 441 is designed in the form of a plate and its top edge is fixed by means of two screws 447, for example, in the mounting-strip 442 which is split for this purpose. The knife blade has a cross-section in the shape of a double Y (as shown especially in FIG. 44) and is formed in this example by a main plate having two edges folded at an angle of 45° against which are added by welding two members 448 which are also folded at 45°. Moreover, in order that the cutting work performed by the knife should be carried out under good conditions, the blade 441 has a decreasing length from the tips of the arms of each Y to the center A of its lower cutting edge, as can be seen from FIG. 40.

The heating counter-plate assembly 12 of rectangular shape has a central opening which is also rectangular and has dimensions corresponding to those of the punch assembly formed by the two main members 405, 406 and the two auxiliary triangular members 407, 408 which slide within said opening. Said heating counter-plate 12 is carried by four vertical rods 124 fixed be-

neath another horizontal plate 127 which is in turn supported by two vertical rods 128 and these latter also slide within guides (not shown) which are rigidly fixed to the frame of the machine. The plate 127 is provided with two holes 461, 462 through which the two punch-supporting rods 421, 422 are permitted to pass freely, and also with a central hole 463 through which the knife-supporting rod 443 passes.

The counter-punch 302 is illustrated in FIGS. 45 and 10 46. No extended description of this counter-punch need be given here since its structural design is the same as that of the counter-punch 302 which was described earlier and corresponding members are designated by the same reference numerals. This counter-punch is therefore essentially constituted by two large rectangular main members 311, 311A and by two small auxiliary members 313, 313A having a triangular cross-section. The only characteristic feature of the punch under consideration lies in the fact that its four constituent members are not juxtaposed but are separated so as to leave a given clearance equal to the thickness of the knife 441 which is intended to slide between said members during its downward movement so as to cut the opening in the piece of material to be turned-in.

25 The operation is as follows:

It is assumed that the piece of material having an opening to be turned-in has been suitably introduced and held in position within the machine, especially by means of a device as hereinabove described, that the punch 401 is in the top position (shown in FIG. 47) together with the knife 441 and the heating counter-plate 12, and that the two small sliding plates 217, 218 which carry the gummed reinforcement 268 and the piece 266 to be turned-in have their top faces in the same plane as the top face of the counter-punch 302.

30 The first stage of the automatic cycle consists in the simultaneous downward motion of the punch 401 and of the heating plate 12 which are applied respectively against the counter-punch 302 and against that portion of the member 266 which rests on the small plates 217, 218 (as shown in FIG. 48), where upon the knife 441 moves down from the position shown in full lines to the position shown in chain-dotted lines and performs within the member 266 and incision having the shape of a double Y between the punch and the counter-punch.

35 The knife moves upwards (as shown in FIG. 49) and the heating counter-plate 12 remains in position while the insetting punch 401 moves downwards and folds downwards at right angles the edges of the opening to be turned-in.

40 The punch 401 moves upwards, the counter-punch 302 also moves upwards (FIG. 50) in such manner that the contacting faces thereof are located slightly beneath the underface of the small plates 217, 218 in order to permit of turning-in.

45 In the following stage, the members constituting the punch 302 and especially its two main members 311, 311A move laterally away from each other (as shown in FIG. 51) so as to turn-back the edges of the opening beneath the two sliding plates 217, 218.

50 The final operation consists in applying the top face of the counter-punch 302 against the turned-in edges of the piece which are retained by the heating counter-plate 12 in order to effect gluing by means of the gummed piece 268 after relative withdrawal of the two sliding plates 217, 218.

It then only remains to allow the elements of the machine to return to their initial positions, to remove the piece whose opening has just been turned-in and to replace it with a new piece.

As is readily apparent, the invention is not limited to the embodiments herein described with reference to the accompanying drawings; depending on the applications which are contemplated, modifications can accordingly be made without thereby departing either from the scope or the spirit of the invention.

I claim:

1. A machine for turning-in the marginal portion of an opening in a workpiece of flexible fibre material, said machine comprising: a frame (1), a horizontal support plate (218) carried by said frame and provided with an aperture the dimensions of which are those of the opening in the workpiece after said marginal portion has been turned-in, said support plate being split into a plurality of segmentary plates surrounding said aperture, said support plate having a top surface, an under surface and an edge around said aperture, said support plate being adapted to support said workpiece laid flat upon its top surface with the said marginal portion overhanging said edge, an insetting ram (57 or 301) with an end face mating with said aperture, means moving said ram vertically into and out of said aperture to fold said marginal portion downwardly at right angle to said plate, a plurality of folding back members (56, 57 or 311, 311a) mounted on said ram, means moving said folding back members horizontally under said under surface of said support plate from a retracted position to an expanded position for flattening against said under surface, said marginal portion already turned down at right angle, said folding back members moving means comprising pressing means (13, 302) pressing said folding back members upwardly toward the under surface of said support plate to press said marginal portion against said under surface, counter-plates (12) located above said support plate, means (123, 128) reciprocating said counter-plates vertically and comprising power means pressing said counter-plates against said top surface of said support plate, and displacement means moving said segmentary plates in their common own plane away from said aperture to release said turned-in marginal portion.

2. A machine according to claim 1, wherein said insetting ram and said folding-back members consist of structural members having an upper edge and means pivoting said members about horizontal axes along their upper edges.

3. A machine according to claim 1, wherein said insetting ram consists of a solid punch and said folding-back members form a counter-punch having an end face corresponding to said end face of said insetting ram in retracted position of said folding-back members.

4. A machine according to claim 3, wherein said folding back counter punch consists of two main parallel members having a rectangular cross-section and internal faces facing one another, the extremity of said internal faces of said main members being bevelled, said folding back counter-punch further comprising two prisms having the shape of isosceles triangles fitting between said bevelled extremities.

5. A machine according to claim 4, further comprising a support, said two main members and said two triangular prisms being slidably mounted on said support

in two perpendicular directions, restoring spring means for urging said main members and triangular prisms together, and central cams for urging said main members and triangular prisms against the force of said restoring spring means.

6. A machine according to claim 3, wherein said machine further comprises a knife, and means slidably mounting said knife within the interior of one of the two elements constituted by said punch and said counter-punch.

7. A machine according to claim 6, wherein said knife consists of a plate having a cross-section in the shape of a double Y and said insetting punch consists of two parallel main members having a rectangular cross-section and internal faces, the extremities of said internal faces being bevelled, said insetting punch further comprising two auxiliary members in the form of prisms having the shape of isosceles triangles fitted between said bevelled extremities, said knife being slidably mounted between the opposite face of said main and auxiliary members, the structure of said counter-punch being similarly made up of two main and auxiliary members between which is left an interval at least equal to the thickness of said knife.

8. A machine according to claim 7, wherein said knife consists of a blade having a cutting edge, said blade having a decreasing length from the extremities of the arm of each Y to the mid-point of the length of said cutting edge.

9. A machine according to claim 6, further comprising vertical guide means rigidly secured to said structural frame, rod means slidably mounted within said vertical guide means, said insetting punch being carried by said rod means, further vertical guide means rigidly secured to said structural frame, further rod means slidably mounted within said further vertical guide means, said knife being carried by said further rod means, a drive shaft rotatably mounted in said structural frame, cams carried by said drive shaft, and a lever system operatively connecting said rod means and further rod means to respective cams on said drive shaft.

10. A machine according to claim 1, wherein said insetting ram and said folding-back members consist of structural members with an upper edge and having an L-shaped cross-section and means for pivoting them about horizontal axes along the upper edges thereof, said machine further comprising folding back member restoring spring means, vertical guide means rigidly secured to said frame and rod means slidably arranged within said vertical guide means, said insetting ram, said folding back members and said support plates being carried by said rod means, said machine further comprising further vertical guide means rigidly secured to said frame, further rod means slidably mounted within said further vertical guide means, and a wedge secured to said further rod means and capable of displacing said folding back members in opposite direction to the force of said folding back members restoring spring means.

11. A machine according to claim 1, further comprising vertical guide means rigidly secured to said frame and rod means slidably mounted within said vertical guide means, said insetting ram, said folding-back members and said support plate means being carried by said rod means.

12. A machine according to claim 11, further comprising a common drive shaft rotatably mounted in said

structural frame, cams carried by said common drive shaft, and a lever system operatively connecting said cams to said sliding rod means.

13. A machine according to claim 1, further comprising a common support, said workpiece supporting plate

means comprising two C-shaped plates in oppositely facing relation and capable of sliding on said common support under the action of said displacement means.
